UNITED STATES PATENT OFFICE.

GEORGE W. SCOTT, OF CHICAGO, ILLINOIS, ASSIGNOR TO THE PULLMAN'S PALACE CAR COMPANY, OF SAME PLACE.

CAR-TRUCK.

SPECIFICATION forming part of Letters Patent No. 635,151, dated October 17, 1899.

Application filed October 17, 1898. Serial No. 693,735. (No model.)

To all whom it may concern:

Be it known that I, GEORGE W. SCOTT, of Chicago, in the county of Cook and State of Illinois, have invented certain new and useful Improvements in Car-Trucks, of which the following is a specification.

This invention relates to car-trucks, being more particularly designed for use as a freight-car truck, and has for its object to provide a metallic car-truck which shall be simple and strong in construction, free from complicated and costly parts, and consequently adapted to be readily repaired; and to these ends the invention consists in certain novel features which I will now proceed to describe, and will then particularly point out in the claims.

In the accompanying drawings, Figure 1 is a plan view of a truck embodying my invention, a portion thereof being in plan section. Fig. 2 is a side elevation of the same, partly in vertical section, longitudinally of the truck. Fig. 3 is an end elevation, partly in vertical section, transversely of the truck. Fig. 4 is a plan view, Fig. 5 a side elevation, and Fig. 6 an end elevation, of the upper cross-tie, which also supports the brakes. Fig. 7 is a side elevation, and Fig. 8 a plan, of the lower cross-tie. Fig. 9 is an elevation, on an enlarged scale, of the combined bolster-guide and spring-seat detached. Fig. 10 is a vertical sectional view of the same. Fig. 11 is an elevation of the bolster-guide spring-cap detached; Fig. 12, a plan view, and Fig. 13 a vertical sectional view, of the same; and Fig. 14 is an elevation, partly in vertical section, of the center plate.

In the said drawings, 15 indicates the upper or compression member of the truck-bolster, and 16 the lower or tension member, the two members being separated at their centers by a strut or king-post 17 and the tension member being provided at its end with a head or enlargement 18, that extends upward to engage the ends of the compression member and downward to engage with the spring-cap. The upper or compression member of the bolster is straight, while the lower or tension member is inclined upward from the center toward each end to meet the upper member, and spacing-blocks 19 are in-

terposed between the two members at their points of junction.

20 indicates the upper arch-bars, and 21 the lower arch-bars, between which is interposed the combined bolster-guide and spring-seat 22. (Shown in detail in Figs. 9 and 10 of the drawings.) This part is a casting comprising a bed-piece or seat 23, upon which the springs 24 rest, and upright guides 25, integral with said bed or seat and apertured, as shown 60 at 26, for the passage of the column-bolts 27. The upper ends of the guides 25 are provided with lateral flanges 28, between which the upper arch-bar is seated, while the bed-piece 23 is provided with lateral flanges 29 on its under 65 side, between which the lower arch-bar 21 is seated.

30 indicates the cap, which is provided with lateral guideways 31 to fit the guides 25 and with an inclined bearing-surface 32 and horizontal bearing-surfaces 33, upon which the lower or tension member of the bolster rests. 70

34 indicates the side bearings, which are mounted on top of the bolster above the caps 30 and which are secured in position by means 75 of bolts 35, which pass downward through the bearings, filling-blocks 19, bolster, and cap. Bolts 36 are also employed to secure the ends of the bolster directly to the caps.

37 indicates the lower cross-tie, which, as 80 shown in detail in Figs. 7 and 8, consists of a channel member 37^a, to the ends of which are secured plates 37^b, which extend underneath the tie-bars 38 and are secured in position by the column-bolts 27. This cross-tie 85 furnishes a strong and simply-constructed connection between the diamond frames at their lower sides and is secured in position by the column-bolts without the necessity of separate fastening devices. 90

The diamond frames are connected together at their upper sides by means of a cross-tie 39, composed, as shown in detail in Figs. 4, 5, and 6, of two transverse angle-bars 39^a, connected at their ends by cross-pieces 39^b, of 95 plate form, and secured in position by means of the column-bolts 27. This upper cross-tie not only serves to connect the diamond frames and, in conjunction with the lower cross-tie, firmly binds the truck together and 100

preserves the fixity and relative position of the column-guides, but it also serves as a means for the attachment of the brake-rigging in the case where the truck is provided with inside 5 brakes, as in the construction shown. In this construction I employ a guide or support for the dead-lever 40, consisting of a bar 41, bent to form a loop to receive the end of the lever and having one arm of the loop extended 10 across and secured to the two members 39^a of the upper cross-tie, while the other arm is bent at right angles and secured to the vertical face of one of said members. This construction serves not only to provide a firm 15 attachment for the dead-lever, but also to securely cross-brace the upper cross-tie. The live-lever guide 41^a is secured to the vertical face of the other member 39^a of the upper cross-tie, the ends of the guide being bent up 20 at right angles to the body for this purpose, as shown in Fig. 2 of the drawings. The brackets 42, from which the brake-beams are suspended, are also secured to the transverse members 39^a of the upper cross-tie 39, so that 25 the entire brake-rigging is suspended from this upper cross-tie.

The center plate 43, as shown in detail in Fig. 14, is riveted or bolted directly to the upper member 15 of the truck-bolster, the 30 rivets passing directly through the bearing-surface of the plate instead of through outlying flanges, as in the usual construction, and the countersunk rivets or bolt-holes 44 serve as convenient reservoirs for the lubricant. 35

It will be noted that the combined column-guide and spring-seat furnishes a strong and simple structure well adapted for its purposes, the lateral flanges serving to firmly 40 hold the arch-bars and relieve the column-bolts from side strains. The construction of the spring-cap and the mode of securing it to the end of the bolster is also particularly advantageous, and the mode of cross-tying the 45 diamond frame serves to maintain the proper relative position of the column-guides, and thus insure freedom of motion for the spring-caps and bolster. The mode of supporting the 50 brake-rigging not only serves to strengthen the truck-frame, but also insures the maintaining of the proper relative position between the brakes and the wheels.

I claim—

1. In a car-truck, the combination, with 55 spring-caps, of a bolster comprising a compression member, and a tension member extending between the compression member and spring-caps, supporting the former vertically upon the latter, and provided at its 60 ends with upward projections which abut against the ends of the compression member and with downward projections which abut against the outer faces of the caps, substantially as described.

65 2. In a car-truck, the combination, with

spring-caps, of a bolster comprising a compression member and a tension member separated at their centers and converging at their ends, the tension member being secured at its ends between the caps and compression member, filling-blocks located in the meeting angles of the two bolster members, side bearings located on the bolster above the caps, and securing-bolts passing vertically through said several parts whereby they are secured 75 together, substantially as described.

3. In a car-truck, the combination, with the diamond frames forming the sides of the truck-frame, of upper and lower cross-ties connecting said diamond frames and secured 80 thereto by means of the column-bolts, substantially as described.

4. In a car-truck, the combination, with the diamond frames, of a cross-tie comprising a channel-shaped body and terminal plate-gussets, whereby its ends are adapted to be secured by means of the column-bolts, substantially 85 as described.

5. In a car-truck, the combination, with the diamond frames, of an upper cross-tie comprising two parallel angle-pieces and connecting-plate cross-pieces at their ends, whereby 90 said tie is adapted to be secured by means of the column-bolts, substantially as described.

6. In a car-truck, the combination, with the diamond frames, of a lower cross-tie comprising a channel-shaped body and terminal plate-gussets, and an upper cross-tie comprising two parallel angle-pieces and connecting-plate cross-pieces at their ends, whereby 95 said ties are adapted to be secured by means of the column-bolts, substantially as described. 100

7. In a car-truck, the combination, with the diamond frames, of an upper cross-tie comprising parallel angle members connected at 105 their ends to each other and to the column-bolts, a dead-lever guide or support having one arm extended across and secured to the top flanges of the two parallel members, and the live-lever guide and brake-beam-supporting brackets also secured to said angle members, substantially as described. 110

8. In a car-truck, a lubricated center-bearing, comprising, in combination, a truck-bolster, a center plate having a bearing-surface cup-shaped in form and adapted to receive a correspondingly-shaped projecting bearing-plate on the body-bolster, vertical apertures through said center plate having enlarged recesses at their upper ends formed in said bearing-surface, and rivets securing said center plate to the bolster and countersunk in said recesses, whereby reservoirs for the lubricant are formed, substantially as described. 115 120 125
